US00D634759S

(12) **United States Design Patent**
Farrow

(10) **Patent No.:** **US D634,759 S**
(45) **Date of Patent:** **** Mar. 22, 2011**

(54) **TRAILER MOUNTED WET ABRASIVE SYSTEM**

(75) Inventor: **Nigel Farrow**, West Chester, PA (US)

(73) Assignee: **Farrow Holdings Group, Inc.**,
Philadelphia, PA (US)

(**) Term: **14 Years**

(21) Appl. No.: **29/359,766**

(22) Filed: **Apr. 15, 2010**

(30) **Foreign Application Priority Data**

Feb. 22, 2010 (GB) 4014583

(51) **LOC (9) Cl.** **15-03**

(52) **U.S. Cl.** **D15/27**

(58) **Field of Classification Search** D15/10,
D15/27, 12, 13, 21; 239/668, 656, 655, 675,
239/676, 654, 662, 672, 673; 366/177, 186,

(57) **CLAIM**

The ornamental design for the trailer mounted wet abrasive system, as shown and described.

DESCRIPTION

FIG. 1 is a front isometric view of the trailer mounted wet abrasive system showing my new design;

FIG. 2 is a rear isometric view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The bottom view forms no part of the claimed design.

The dashed lines shown in the figures represent environmental subject matter and form no part of the claimed design.
